UNITED STATES PATENT OFFICE.

RICHARD H. FREITAG, OF AKRON, OHIO.

FILING MACHINE.

Application filed January 16, 1924. Serial No. 686,532.

To all whom it may concern:

Be it known that I, RICHARD H. FREITAG, a citizen of the United States, and a resident of Akron, county of Summit, State of 5 Ohio, have invented certain new and useful Improvements in Filing Machines, of which the following is a specification.

This invention relates to machines for filing, such as used by die and template 10 makers. In this class of work it is desirable that various shapes and grades of files be used at different points on the same job, and it is the purpose of my invention to construct a machine for this work wherein the 15 different types of files are at hand so that they can be readily called into use without changing or adjusting the machine.

With the improved machine herein shown a gang of files is mounted within the 20 machine, each with its own reciprocable carrier, and in operative relation to all of the carriers is a common actuating member. Means are provided to throw any one of said files, or more than one file at a time, into connection 25 with the actuating member. The files which are not in use are located below the work table so not to interfere with the operation of the remaining files.

The machine herein shown is suitable for 30 all types of work of this general nature and is extremely useful and practical. As far as known to me, it is the first practical machine of this type and the description and claims herein are, therefore, entitled to a 35 liberal scope in defining the invention.

In the drawings:

Figure 1 is a vertical section through the machine;

Figure 2 is a section at right angles to 40 Figure 1, the section lines 2-2 on Figure 1 and 1-1 on Figure 2 indicate the points at which the sections are taken, respectively;

Figure 3 is a section on the line 3-3 of Figure 1;

Figure 4 is a plan view of the work table.

In the drawings, 1 represents a work table which is horizontal in the present form of the invention, but which may be arranged at any suitable angle. The table is supported upon standards 2 which are tied together at their lower ends by a transverse shaft 3 arranged in lugs 4 at the base of the standards.

The table 1 is provided with a series of 55 apertures 5, which, in the present form of the invention, are arranged in a circle. De-

pending from the under side of the table and located at the center of the circle is a guide post 6, which is provided with a feather 7, and on the guide post is a reciprocating sleeve 8. At a point on the sleeve is arranged a slide block 9 which is engaged by a crank-pin 10 on the face of a disk 11 that is carried by a rotating shaft 12. The shaft 12 is supported within a bearing plate 13 which is bolted to the under side of the table by brackets 16. The shaft is arranged to be rotated by a motor 14 also secured to the under side of the table, the motor shaft and the shaft 12 having interconnecting worm 70 or spiral gearing indicated by the numeral 15. The motor shaft 17 is supported at its outer end by a bracket 18. The sleeve 8, which has been described, with its operating parts, is the common actuating member referred to in the opening portion of the specification.

The plate 13 is provided with a centrally located opening 20 to accommodate the part 8 and is formed with a plurality of integral 80 bearing sleeves 21 which are arranged in circular relation to register with the openings 5 in the table. Each sleeve has slidably mounted therein a tool carrier 22 in the upper end of which is a collet 23 in which is secured the tool 24 in position to be received in the opening 5. In the machine shown herein, the tools are files and each carrier is arranged to support a different file either in shape or grade as may be needed for the 90 particular work for which the machine is designed. Except for the character of the file, the tool carriers are of similar design and a description of one will suffice for the lot.

The carrier 22 is in the form of a vertical barrel having a keyway 24^a engaging with the bearing sleeve 21. The upper end of the carrier is enlarged and overhangs the sleeve, being provided with a collar 23^a 100 which protects the bearing from filings. The sleeve extends below the plate 13 slightly and at its lower end carries a plate 25 which is held in position by the bolt 26 which operates the collet. A spring 27 surrounds the barrel between the lower end of the sleeve and the plate.

At one side of the bearing 21 is a second bearing 28 in which is slidably mounted a plunger 29 working against a spring 30. 110 The plunger carries upon its lower end a rocking arm 31, one end of which projects

beneath the tool carrier and the other end of which projects beneath a flange 32 on the lower end of the actuating member 8. The plunger 29 is arranged to be elevated to bring its file into operative relation to the actuating member and to project it above the table. In Figure 2, the right hand file is elevated in operative position, while the left hand file is depressed or in inactive position. Each plunger 29 carries at its lower end a bearing block 33 provided with a pin 34 to which is connected a lever 35 pivoted to a pedal 36 which is rotatably mounted on the shaft 3. When an appropriate pedal is depressed the link 35 is actuated to raise its plunger 29, elevating the file and bringing it in position to be actuated by the reciprocating sleeve, which, while the machine is in operation, is in constant motion. As each file is connected to a single treadle, the operator merely selects the file he desires to use, presses the treadle and the file is presented above the table and in rapid reciprocation. Each treadle is provided with a stop 37 designed to limit the downward movement of the plunger and with an adjustable pin 38 which strikes a cross bar 39 on the base of the machine. The pin 38 is so adjusted that when the treadle is depressed the link is thrown slightly past center so that the parts remain in elevated position.

It is believed that the operation of the parts will be understood from the description which has been given and the utility of the machine will be apparent. The arrangement shown provides a quickly operated means for performing many classes of filing work which are required in a single job or in several jobs. One or more files can be placed in operation as desired. Heretofore, single filing machines have been on the market, but I do not know of any multiple filing machine which has been available to the workman, or one which embodies the advantages of the present machine. While the circular arrangement of tools is illustrated, it will be understood that other arrangements are possible and that alternative mechanism may be employed for operating the tools.

Other changes and modifications would suggest themselves to a machine designer and I do not intend to be limited in scope to the exact form or arrangement of parts herein shown and described. The invention is not necessarily limited to filing machines, although its design is for that especial purpose.

60 What is claimed is:

1. A machine of the character described comprising a plurality of reciprocating carriers, a tool in each carrier, a common actuating member therefor adapted to be operated continuously but normally discon-

nected from the tool carrier, and means to place any one of said carriers in operative relation to the actuating member.

2. A machine of the character described comprising a work table, a plurality of tools supported below said work table, an actuating member for reciprocating one or more of said tools, and means to project a tool above the table and simultaneously place it in operative relation to the actuating member. 75

3. A machine of the character described comprising a work table, a plurality of tools supported below said work table, a single actuating member normally disconnected from the tools, and means to place a tool in position to be actuated by the member above the table. 80

4. A filing machine comprising a plurality of reciprocable carriers, a file in each said carrier, a reciprocable member independent of the carriers, a rock arm associated with each carrier and normally in inoperative position with respect to said member, and means to place a selected rock arm 90 in operative position with respect to the said member. 85

5. A filing machine comprising a work table, a plurality of reciprocable carriers, a file in each carrier below the table, a reciprocating member independent of the carriers, a rock arm associated with each carrier and normally in inoperative position with respect to said member, and means to place a selected rock arm in operative position with respect to the said member and elevate the tool above the table. 95

6. A filing machine comprising a work table, a plurality of files in upright position but normally below the work table, and means to simultaneously elevate a selected file above the table and start it in reciprocation. 105

7. A filing machine comprising a work table, a plurality of carriers, files in said carriers, each carrier being capable of reciprocation independently of the other carriers, and means to bring any carrier into operation without changing its position relative to the work table. 110

8. A filing machine comprising a work table, a plurality of carriers which are normally removed from the work table, files in said carriers, each carrier being capable of reciprocation independently of the other carriers, and means operative to cause a carrier to approach the work table and to reciprocate. 120

9. A filing machine comprising a reciprocating member, a plurality of files arranged about the member, a rock arm associated with each carrier, and means to elevate the carrier to bring the rock arm into operative relation to the member. 125

10. A filing machine comprising a work

table, a plurality of files which when in a position of rest are below the work table, means connected with each said file and operable selectively to bring any file from its position of rest to a position above the table, and means to reciprocate the file in its second position.

11. A filing machine comprising a centrally located reciprocating member, a plurality of guides about the member, carriers in the guides, files in the carriers, a vertical plunger adjacent each carrier, a rock lever on each plunger in line with the carrier and the reciprocating member, and means connected to each plunger whereby it may be raised and lowered.

12. A filing machine comprising a work

table having a plurality of holes therein, a file located in each hole but normally below the surface of the table, guiding and carrying members for the files, and means operating upon each carrying member to elevate it so as to project its file through the table and at the same time to start it in reciprocation independently of the other files.

13. In a machine of the character set forth, the combination of a work table, a plurality of tool carriers arranged at the work table, and means for operating any carrier independently of the other carriers without changing its position relative to the table.

RICHARD H. FREITAG.
